UNITED STATES PATENT OFFICE.

FRANK H. RUDAT, OF COLUMBUS, NEBRASKA.

ROTARY-DISK ROAD GRADER.

Application filed November 20, 1922. Serial No. 602,054.

To all whom it may concern:

Be it known that I, FRANK H. RUDAT, a citizen of the United States, residing at Columbus, in the county of Platte and State 5 of Nebraska, have invented certain new and useful Improvements in Rotary-Disk Road Graders, of which the following is a specification.

The invention has for an object to effect 10 improvements in road graders, to enable the use of rotary disks in scraping a road surface and moving the surface material laterally of the road.

Additional objects, advantages and features of invention reside in the construction, arrangement and combination of parts as hereinafter described and shown in the drawings, presenting one embodiment of the invention, wherein,

20 Figure 1 is a plan view of a grader constructed in accordance with the invention,

Fig. 2 is a transverse sectional view thereof,

Fig. 3 is a detail of the disk mounting, 25 and gang bar,

Fig. 4 is a longitudinal sectional view of the device,

Fig. 5 is a detail of the steering means,

Fig. 6 is a vertical cross section of a disk 30 and its mounting,

Fig. 7 is a detail of the adjustable mounting for an end disk on the gang,

Fig. 8 is a top view of the disk mounting.

There is illustrated a grader comprising 35 a main frame 10, broad at its rear part and narrow at the forward part, as may be seen in Fig. 1, the frame being supported at the rear by large rollers 11, which may be weighted, if desired, but preferably are like 40 hollow drums. At the forward part, the frame is supported by a steering roller 12, carried in a caster frame 13 which is provided with a steering yoke 14 projecting forwardly therefrom, and moved by means 45 of a cable 15 wound upon a small steering drum 16 at the lower end of a vertical shaft 17 mounted in a tongue frame 18 projected forwardly from the front end of the frame 10. The upper end of the shaft 17 is provided 50 with a large bevelled gear 19 meshed with which there is a small pinion 20 fixed on the forward end of a steering shaft 21 mounted revolvably upon the upper side of the frame 10 and extending rearwardly to 55 an operator's platform 22 where an upstanding bracket 23 supports the shaft revolvably.

The rear end of the shaft is provided with a hand wheel 24 by which manual steering of the device is accomplished.

The forward end of the truck frame 18 60 is provided with an aperture 18' by which draft connections may be made with the apparatus. The platform 22 at the rear is supported directly upon a transverse rail member of the frame 10 and at its forward end upon a beam 25, which extends across the frame 10. The beam 25 is of channel iron and if desired may be adjusted angularly on the frame 10. A transverse draft beam 26 is mounted intermediately of the 65 forwardly convergent sides of the frame. The beam is adjustable forwardly or backwardly at its ends upon the side members of the frame 10 so as to adjust the angular relation of the beam to the direction of 70 travel of the machine, as desired. In the present instance, the beam is secured by removable pins 27 inserted through the beam 26 and suitable apertures spaced longitudinally on the side members of the frame 10. 75 The beam 26 carries a number of eye couplers 28, three in the present instance, upon which are engaged respectively the forward apertured ends of draft arms 29 extending rearwardly and downwardly, 80 over and behind a disk gang 30, the bars 29 may be connected hinged at their rear lower ends to the beam 31 upon which the 85 gang of disks is mounted. The bars 29 are so secured to the beam 31 as to hold it securely in fixed relation to the perpendicular, but permitting lateral shifting of the beam with respect to the frame 10. The bars 29 are formed of channel iron, and their lower 90 rear ends extend vertically as shown in Fig. 95 6, being provided at the extremities with a suitable pivot fitting 32, riveted to the bar 29 and having a vertically bored portion receiving the spindle bolt 33 which is engaged through knuckles or cars 34 riveted upon the eye beam 31, as shown in Figs. 6 and 8. A nut 35 is engaged on the lower end of each spindle bolt 33.

Upon the top of the disk beam 31, there are mounted a series of clamp mountings 100 36, in the form of saddle and strap elements, between each set of which there is clamped a stud shaft 37, upon which a respective disk 38 is mounted. The disk may be pressed from sheet metal in the customary manner, and may be either flat or slightly dished, as found desirable to suit the work 105 110

2
to which the device is applied; and fixed axially upon each there is a hub element 39, having a forward cap portion 40 which forms a continuation of a barrel 41 of the hub, the cap portion being inserted snugly through a proper aperture in the disk 38 the barrel having a flange 42 thereon intermediately of its length, which flange is fitted snugly against the back face of the disk and bolted thereto with a suitable number of bolts and nuts. The rear end of the barrel is provided with a peripheral circumscribing flange 43, and the saddle and strap element of the clamp mounting 36 are provided with recesses having circumscribing grooves, and adapted to engage snugly over and enclose this flange, and the adjacent barrel portion to serve as a dust cap and retainer and permitting free rotation of the hub while the shaft 37 is securely clamped. The shaft 37 is fitted snugly and revolubly in the hub and preferably stops short of the cap end at the forward part to provide a small space to accommodate oil or other lubricant.

For the support of the disk gang, links 45 are connected thereto adjacent each end by means of swivel eyes to which the lower ends of the links are hooked. The upper ends of the links are swivelly connected eccentrically to gears 47, mounted upon respective brackets 48 on the cross beam 25. The gears are mounted in a plane with the beam 25 so that the disk gang may be adjusted laterally in either direction. Each of the gears 47 is engaged by a respective worm 49 on a shaft 50 extended inwardly from the worm, to a point closely adjacent the steering wheel 24 where they are provided with hand wheels 51 by which the raising and lowering of the gang at either or both ends may be effected. The worms at each side are independently operable, so that by this means, not only the depth of cut but the slope produced may be controlled.

At a suitable point on the cross beam 25, a gear 52 is mounted in a transverse plane, with which a worm 53 is meshed. The bracket for the gear 52 is extended downwardly from the beam 25 to one side of the machine and the worm 53 is arranged diagonally so that its shaft 54 may extend upwardly to the opposite side of the machine closely adjacent one of the hand wheels 51, where a similar hand wheel 55 is provided on the shaft 54. A link 56 is swivelled upon the gear 52 eccentrically thereof, and extended transversely of the machine as far as possible, and connected swivelly to the beam 31, the arrangement being such that the link 56 extends as nearly horizontal as practicable. This mechanism is utilized to adjust the disk gang transversely, as may be required.

In the operation of the machine, the angle of the disk gang with respect to the direction of travel of the machine may be adjusted by the draft beam 27 as required. In case a considerable degree of angular adjustment should be necessary, it is possible to also adjust the bar 25 similarly, but for moderate differences, it is only necessary to adjust the draft beam. The terminal disk, or one of the terminal disks may be made adjustable after the manner indicated in Fig. 7 longitudinal slots being formed in the terminal flanges of the beam 31, which is curved slightly forward. Upon the top of this beam there is clamped a plate 56, having transverse slots 57 which may be adjusted at right angles to the slots 58 in the beam 31. Upon the head portion of the plate 56 there is mounted a stud shaft 57 with a saddle and strap mounting similar to that before described. Bolts and nuts being engaged in the slots 57 and 58, the plate 56 may be clamped in various angular relations to the supporting portion of the beam 31, and may also be adjusted transversely, and longitudinally of the beam.

If desired, an auxiliary spreader board 60 may be hingedly mounted upon the side of the frame 10 and rearwardly of the disk gang, to spread earth discharged at one side by the disk gang, as may be required.

This device will be found especially useful in working earth and gravel roads, the disks being especially efficient in throwing toward the middle of the road material which has washed to one side, or material which it is necessary to excavate, and the spreader will distribute this material smoothly and in a more suitable condition for rolling than could material produced by a simple blade scraper. The device is also suitable for use as a roller, by hoisting the gang, as will be readily understood.

It is also very useful in shaping a roadway itself, especially where a roadway is badly rutted and comprises hard material. In all operations, the power required for draft is reduced to a minimum by reason of the easy rolling of the disks when engaged with material excavated or moved thereby.

It should be noted (see Fig. 2) that the wheels 11 are shown inclined upon their tread surfaces, and this is done in order that the machine may travel at a proper angle upon the customary sloping sides of a roadway, and also to better resist the lateral thrust transmitted to the frame by the disks and the scraper board. The wheel 12 may be similarly constructed, if desired.

What is claimed:—

1. In a machine of the character described, a wheeled frame, a transverse beam adjustable angularly with respect to the fore and aft axis of the machine, a plurality

of bars having universal pivotal connection therewith, and being curved downwardly at their rear parts, a scraper mounting member having hinged connection with the lower ends of the bars and extending transversely of the frame, and means to adjust the scraper mounting member vertically at either side.

2. In a machine of the character described, a wheeled frame, a transverse scraper element thereon, vertically and laterally movable, large gears mounted on the upper part of the machine in a transverse plane, respective links eccentrically connected to the gears and extending directly downward to the scraper element and having swivelled connection both with the gears and with the scraper element, another gear mounted in a transverse plane on said frame, a link swivelled eccentrically on the gear and also so connected to the scraper element at a distance from the gear laterally of the frame, and respective means to oper-

ate said first two and the last named gears alternatively.

3. In a machine of the character described, a wheeled frame, a second frame element vertically and transversely adjustable on the first frame, a multiplicity of disk elements on the second frame arranged in closely overlapped relation arranged transversely of the first frame, and mounted for rotation on axes extending in a fore and aft direction, the outermost of the disks having a separately adjustable mounting whereby adjustment of angular relation to the remainder of the gang may be made, and also for adjustment of the outermost of the disks bodily for position transversely and longitudinally.

In testimony whereof I have affixed my signature in presence of two witnesses.

FRANK H. RUDAT.
